UNITED STATES PATENT OFFICE.

WILLIAM ELMER, JR., OF PITTSBURG, PENNSYLVANIA.

WINDOW CONSTRUCTION.

982,580.

Specification of Letters Patent. Patented Jan. 24, 1911.

Original application filed July 26, 1907, Serial No. 385,644. Divided and this application filed April 26, 1909. Serial No. 492,208.

To all whom it may concern:

Be it known that I, WILLIAM ELMER, Jr., a citizen of the United States of America, residing in Pittsburg, in the county of Allegheny, in the State of Pennsylvania, have invented a certain new and useful Improvement in Window Construction, of which the following is a true and exact description, reference being had to the accompanying drawings, which form a part thereof.

My present invention relates to window frame constructions and particularly to window frame constructions for factory and other large buildings, and the object of the present invention is to provide a simple and effective metallic window frame construction particularly adapted for use in buildings of the character referred to where it is desirable to use more than a single pair of sashes for each window opening.

The window frame construction claimed herein is especially adapted for use with the particular sash balancing arrangement disclosed herein but claimed in my prior application, Serial No. 385,644, filed July 26th, 1907, of which this application is a division.

The various features of novelty which characterize my invention are pointed out with particularity in the claims annexed to and forming a part of this specification. For a better understanding of my invention, however, and the advantages possessed by it, reference may be had to the accompanying drawings and descriptive matter in which I have illustrated and described one of the forms in which my invention may be embodied.

Of the drawings, Figure 1 is an elevation of a side of a building showing the frame for one window opening and a portion of an adjacent opening. Fig. 2 is a sectional elevation taken on the line 2—2 of Fig. 1. Fig. 3 is a sectional elevation taken on the line 3—3 of Fig. 5. Fig. 4 is a sectional elevation taken on the line 4—4 of Fig. 5 but with the top sash down from its closed position, and, Fig. 5 is a view taken similarly to Fig. 2, showing a portion only of the structure there shown but on a larger scale.

In the construction shown in the drawings, the window frame for each window opening is formed by vertical frame members A and top frame members B and B', and bottom frame members C. The frame members A, shown best in Fig. 4, are in the form of

metal I beams of commercial form and having the usual beveled flanges A', and preferably parts B, B', and C are formed of metal. Guideways for four sashes, E', E², E³, and E⁴, are formed by the flanges A' of the side members A and spacing ribs F, preferably of metal, secured to the web of the I beam A by bolts F². As shown in Fig. 4, where window openings are side by side, the bolts F² may pass through the web and secure in place not only the ribs F for one set of sashes but also the ribs F' for the adjacent set.

The sashes E', E², E³, and E⁴, which may be of the usual construction, are connected together in pairs by flexible cords or chains G and G' fastened to screws H secured to the sashes. The upper and lower sashes E' and E⁴ being connected by the chains G, and the intermediate sashes E² and E³ by the chains G'. Each chain G passes over a pair of guides or pulleys G³ located at the upper end of the window opening, one adjacent each flange A' of the I beam A. Similarly, the cord G' passes over a guide or pulley G⁴ having its center located above the middle rib F. The pintles G⁵ for the guide rolls are journaled in plates G⁶ secured to the web of the beams A by bolts G⁷ and suitable spacers. As shown in Fig. 4, the sashes E' and E⁴ working in the guide ways adjacent the I beam flanges are beveled to correspond to the bevel of the flanges A'.

By this arrangement it will be observed that each of the sashes may be moved to the desired cleaning or repair level; for instance, under ordinary circumstances to the level occupied in Fig. 1 by the sash E⁴. As the window frames are formed of metal they are very durable and are not liable to warp out of shape.

One of the advantages of the window frame construction is found in the effective use which it permits of commercial forms of metal bars, thus cheapening and facilitating the manufacture of the frames.

Having now described my invention, what I claim as new, and desire to secure by Letters Patent, is:

1. The combination in a window frame adapted to receive a plurality of movable window sashes in its window opening, of I beams having the usual beveled flanges at opposite sides of the window opening, a rib or ribs secured to the web of each of said I beams, and with the flanges of the beam

- forming guide ways for the window sashes, of sashes working in said guide ways, the sashes working in the guide ways adjacent the flanges of the I beams being beveled to correspond to the bevel of said flanges.
2. The combination in a window frame provided with a plurality of window openings and adapted to receive a plurality of movable window sashes in each opening, of an I beam separating an adjacent pair of window openings, and ribs secured to the opposite sides of the web of said beam and with the flanges of the beam forming guide ways for the window sashes in the window openings at the two sides of the I beam.
3. A window frame having its sides

formed by I beams having the usual beveled flanges and having guideways for a plurality of pairs of sashes formed by the flanges of the I beams and parallel ribs secured to the webs of the beams, a sash in each guideway, a flexible counterbalancing connection between each sash and another sash, and guide rolls for the flexible connections secured to the I beams at the upper end of the window frame, the sashes working in the guide ways adjacent the I beam flanges being beveled to correspond to the bevel of said flanges.

WILLIAM ELMER, JR.
